CLAIM

The ornamental design for a horizontal bifold cell phone wallet, as shown and described.

DESCRIPTION

FIG. 1 is a perspective view of a horizontal bifold cell phone wallet according to an embodiment showing my new design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the horizontal bifold cell phone wallet in an open condition;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The present application is directed to the design illustrated in the drawings. Portions of the cell phone wallet and the environment shown in broken lines form no part of the claimed design.
